UNITED STATES PATENT OFFICE.

WILLIAM J. DAVID, OF LOS ANGELES, CALIFORNIA.

APRON.

Application filed April 20, 1926. Serial No. 103,233.

This invention relates to improvements in aprons which may be used by barbers, surgeons, dentists, patients, and for other purposes.

An object of this invention is to provide an improved apron having a neck band which is designed to be held snugly about the neck of the wearer, and which has a metallic fastening part for fastening the

10 neck band in the desired position, which fastening part is readily removable. The object of having this construction is that in sending the aprons to a laundry to be laundered, it is undesirable that there be

15 any metallic parts on the apron, as these parts not only are apt to become damaged in themselves, but are apt to damage machinery in the laundering. By the improved construction the metallic fastener part can be

20 easily detached and the complete apron can be sent to the laundry free from any metallic parts whatsoever, so that the damage which might otherwise occur to the machinery during the laundering will thus be completely eliminated.

Another object of this invention is to provide an improved apron having a hook on one end of its neck band and an improved construction on the other end of the neck band adapted to be engaged by the hook, and which is of simple and durable construction, and which can be easily constructed and will provide for adjustment of the neck band.

35 With the foregoing and other objects in view which will be made manifest in the following detailed description and specifically pointed out in the appended claims, reference is had to the accompanying drawings for an illustrative embodiment of the invention, wherein:

Figure 1 is a partial perspective view of the improved apron, illustrating the neck band as being open or detached.

45 Fig. 2 is a horizontal section through the neck band illustrating the manner of engagement between the hook and the opposite end of the neck band.

Fig. 3 is a partial inside elevation of the improved neck band, the hook shown as having been removed, and

50 Fig. 4 is a view similar to Fig. 3 illustrating the hook in applied position.

Referring to the accompanying drawings wherein similar reference characters designate similar parts throughout, the improved apron consists of a body 10, on which there

is provided a suitable neck band 11. The body may be of any desirable material, and adjacent one end of the neck band on the inner side thereof there is a small strip of fabric 12. This fabric is secured to the neck band 11 by stitching indicated at 13 arranged at its top and bottom edges and provides a loop which is open at both ends and which is arranged longitudinally of the neck band. The hook which is employed may be of any desirable construction, but is preferably formed of a single piece of wire bent centrally, as indicated at 15 to provide a point. It is then reversely bent upon itself, 70 as indicated at 16, to provide a shank 17 adapted to be disposed in the loop provided by the neck band and the strip of fabric 12. The ends of the piece of wire are curled at 18 forming portions disposed adjacent the shank. The extremities, however, are slightly spaced from the shank. If desired, a conventional hook can be employed and the curled portions 18 which are usually arranged to have their ends engaging the shank 80

to form eyes can be stretched slightly to make the construction shown in Fig. 4. The curled portions 18 engage the edge of the fabric strip 12 remote from the end of the neck band to which the hook is applied, and thus serve to prevent the hook from being pulled through the loop in the direction of the end of the neck band. However, the hook can be removed from the loop in the opposite direction by forcing the hook rearwardly away from the end of the neck band and then causing the shank to be swung away from the neck band. In this manner the complete hook can be readily twisted out of the loop, so that it can be detached from the apron on sending the apron to the laundry. When the apron is returned from the laundry, the hook can be again applied by forcing the point 15 to enter the loop and then swinging the shank against the neck band, causing the hook to assume the position shown in Fig. 4.

On the other end of the neck band suitable means is provided for engagement by the hook to hold the neck band of the apron in closed position. The preferred form of construction is to attach a separate piece of tape 19 to the neck band and causing this tape to form a plurality of pleats 20, as clearly shown in Figs. 1 and 2. These pleats 20 are open toward the rear of the apron or toward the center of the neck band and the hook

can be caused to engage any pleat in the manner shown in Fig. 2, thus providing for the adjustment. The tape 19 which is pleated has its top and bottom edges stitched to the neck band. If desired, these pleats instead of being formed by a separate piece of tape can be formed by pleating the top of the body 10 of the apron on stitching it to the neck band 11.

10. From the above described construction it will be appreciated that the improved apron has only a single metallic fastener part, and this fastener part can be readily removed and applied, so that on sending the aprons 15 to the laundry there will be no fasteners to become lost or damaged or which will damage machinery in the laundry. Furthermore, the improved construction provides for an easy, quick and efficient adjustment 20 of the neck band to the body of the person wearing the apron.

It will be understood that various changes in the detail of construction may be made without departing from the spirit or scope 25 of the invention as defined by the appended claims.

I claim:

1. An apron having a neck band, a strip of fabric secured by its top and bottom 30 edges to the interior of the neck band adjacent one end thereof forming a loop, a hook having a shank extending through the loop and having a portion engageable upon the ends of the strip remote from the mentioned 35 end of the neck band so as to prevent the hook from being pulled through the loop,

and means provided upon the other end of the neck band adapted to be engaged by said hook.

2. An apron having a neck band, a strip 40 of fabric secured by its top and bottom edges to the interior of the neck band adjacent one end thereof forming a loop, a hook formed of a single piece of wire bent centrally to provide a point and then reversely bent to 45 provide a shank positioned in the loop, the ends of the piece being bent adjacent the shank so as to be engageable upon the edge of the strip remote from the mentioned end of the neck band, thus preventing the hook 50 from being withdrawn through the loop in one direction, but permitting it in the other, and means provided upon the other end of the neck band adapted to be engaged by the 55 hook.

3. An apron having a neck band, a hook secured to one end thereof, there being a plurality of pleats provided upon the other end of the neck band which are open toward the center of the neck band and any of 60 which are engageable by the hook.

4. An apron having a neck band, a hook detachably secured to one end of the neck band, there being a plurality of pleats provided upon the other end of the neck band 65 which are open toward the center of the neck band and any of which are engageable by the hook.

In testimony whereof I have signed my name to this specification.

WILLIAM J. DAVID.
